United States Patent Office.

JOHN SANDERSON, OF FREDERICKSBURG, OHIO.

Letters Patent No. 77,103, dated April 21, 1868.

IMPROVED BRIDGE.

The Schedule referred to in these Letters Patent and making part of the same.

TO ALL WHOM IT MAY CONCERN:

Be it known that I, JOHN SANDERSON, of Fredericksburg, in the county of Wayne, and in the State of Ohio, have invented certain new and useful Improvements in Bridges; and do hereby declare that the following is a full, clear, and exact description thereof, reference being had to the accompanying drawings, and to the letters of reference marked thereon.

In the annexed drawings, making part of this specification, B B represent a series of cross-ties or ribs of a bridge, which are intended to be cast of metal, or which may be made of wood if desirable, but I propose generally to make this bridge of metal. Cast upon each side of these ties or ribs is a series of wings, A A, some of which are provided with lugs upon their edges; and some with recesses, into which the lugs are fitted, for the purpose of keeping the sections thus formed by the ties and their wings from moving laterally out of position.

The wings are slightly tapering from top to bottom on their edges, so that when the sections are placed together, with the wings in line, and bearing against each other, as represented, the bridge will have a suitable arch.

Each section is secured to its contiguous section by means of form-bolts, suitably distributed, so that the whole will be securely bound together.

Three wings are here represented on each side of each cross-tie, and they meet at the centres of the ties. The centre wings may be left off when only a single track is required.

The bridge of course is covered with flooring, as usual.

Having thus fully described my invention, what I claim as new, and desire to secure by Letters Patent, is—

The bridge herein described, composed of sections, consisting of the cross-ties or ribs B B and wings A A, provided with lugs and recesses, as described, the several sections being bolted together as and for the purpose set forth.

In testimony that I claim the foregoing, I have hereunto set my hand and seal, this 20th day of February, 1868.

Witnesses:

G. W. FIRESTONE,
W. S. PEPPARD.

JOHN SANDERSON. [L. S.]
